CLAIM

The ornamental design for a heater control panel for an automobile, as shown and described.

DESCRIPTION

FIG. 1 is a front elevational view of a heater control panel for an automobile in accordance with my new design; FIG. 2 is a top plan view thereof;

FIG. 3 is a bottom plan view thereof;

FIG. 4 is a left side elevational view thereof;

FIG. 5 is a right side elevational view thereof;

FIG. 6 is a first side perspective view thereof; and,

FIG. 7 is a second side perspective view thereof.

The rear view and rear surfaces of the heater control panel form no part of the claimed design. The heater control panel is configured to be mounted to an automobile. The mounting surfaces of the heater control panel, shown in broken lines in FIGS. 1 to 7, form no part of the claimed design since the inside surfaces are hidden when the heater control panel is mounted to the automobile.
